COMBINED ASH TRAY, SIGNAL, AND ADVERTISING DEVICE

Albert Kiibus, Rego Park, N. Y.

Application April 27, 1953, Serial No. 351,405

1 Claim. (Cl. 340—321)

1

This invention relates to ash trays and more particularly to a combined ash tray, signal and advertising device.

It is an object of the present invention to provide an ash tray provided with a central display portion in which advertising matter is exhibited, the interior of the display portion being illuminated by a small electric lamp having a switch actuatable from the exterior portion.

It is another object of the present invention to provide an ash tray of the above type wherein the light which illuminates the advertising matter will also be utilized to attract the attention of waiters or the like in restaurants and bars.

Other objects of the present invention are to provide a combined ash tray, signal and advertising device bearing the above objects in mind which is of simple construction, inexpensive to manufacture, has a minimum number of parts, is easy to use and efficient in operation.

For other objects and a better understanding of the invention, reference may be had to the following detailed description taken in connection with the accompanying drawing, in which:

Figure 1 is a side elevational view of a combined ash tray, signal and advertising device embodying the features of the present invention;

Fig. 2 is an exploded perspective view of the parts comprising the present invention and

Fig. 3 is a bottom plan view of one of the parts shown in Fig. 2.

Referring now more in detail to the drawing, there is shown a combined ash tray, signal and advertising device, referred to collectively as 10, and including a circular metallic ash tray portion 11, substantially as illustrated.

The bottom wall 12 of the ash tray portion 11 is formed with an upwardly-stamped circular portion 13 provided with a plurality of spaced openings 14, as shown in Fig. 2.

An intermediate portion 15 is provided and consists of a circular top wall 16 integrally formed with an outwardly flared peripheral side wall 17, the bottom edges of side wall 17 being adapted to fit snugly over the raised portion 13 at the outer periphery thereof, as shown in Fig. 1.

The top wall 16 is provided with a plurality of spaced openings 18 lying vertically with the openings 14 in the ash tray portion 11.

An S-shaped bracket 19 is secured to the top of intermediate portion 15 by means of a screw 20, the upper end of bracket 19 fixedly mounting an electric lamp socket 21 in suitable manner. A lamp 22 is screwed into socket 21. The intermediate portion 15 and bracket 19 are both formed of conductive metal, for example copper.

2

A micro-switch 23 is mounted near the periphery of top wall 16 and includes the switch proper (see Fig. 3) 24, the push button 25 and a bearing mounting 26 securing the body portion 24 to the top wall 16 and providing a bearing guide for the push button 25.

One terminal of socket 21 is connected to a wire 27 which passes downwardly through an opening in the top wall 16 where it is connected to one terminal of micro-switch 23, the other terminal of socket 21 being grounded to the bracket 19 and intermediate portion 15. A dry cell battery 28 (Fig. 3) is disposed intermediate ash tray portion 12 and intermediate portion 15, one terminal of battery 28 being connected to the intermediate portion 15 by means of a resilient conductor 29 and the other terminal of battery 28 being connected to one terminal of micro-switch 23 by means of a wire 30. Thus, when the push button 25 is pressed downwardly to close the circuit, the lamp 22 will be illuminated, remaining illuminated until the push button 25 is again pressed downwardly to open the micro-switch 23.

A frustro-pyramidal hollow housing 31 is provided and consists of a top wall 32 and window openings 33, substantially as illustrated. The bottom of housing 31 is open and receives therein the clamp 19, socket 21 and lamp 22. Downwardly extending, threaded studs 34 are provided at each corner of housing 31 and are adapted to pass downwardly through the vertically aligned openings 18 and 14 (Fig. 1) the studs being secured therein by means of nuts 35 abutting the adjacent face of upwardly stamped portion 13. Thus, the housing 31, intermediate portion 15 and ash tray portion 11 are releasably secured together by means of the nuts 35, as will be obvious. The top wall 32 of housing 31 is provided with a circular opening in which is positioned a translucent hemispherical dome 36, which serves to attract the attention of waiters or waitresses in restaurants and bars when illuminated from within.

Suitable advertising matter 37 is displayed within each of the window openings 33. Preferably this advertising matter will be on translucent or transparent material, permitting the same to be illuminated in a striking manner when the lamp 22 is illuminated.

Preferably the advertising matter 37 will consist of inner and outer panes of glass adapted to be retained behind windows 33, between which will be disposed the advertising matter printed on suitable paper.

By removing the nuts 35, the three main parts of the device may be separated (Fig. 2), permit-

ting access to the bulb 22 and to battery 28, to be replaced when necessary.

It will be apparent to those skilled in the art that the various parts of the invention may be formed of plastic, including the intermediate portion 15 with necessary changes in the wiring.

Thus, the combined ash tray, signal and advertising device 18 when properly mounted upon a table in a restaurant or bar, can be used for an ash tray, utilizing the portion 11, and also to display advertising matter utilizing the housing 31. When it is desired to attract the waiter's attention, the push button 25 will be pressed, illuminating the interior of housing 31 and sphere 36, thereby attracting the waiter's attention in a visual manner. This illumination will also draw the user's attention to the advertising matter mounted in the windows 33.

While various changes may be made in the detail construction, it shall be understood that such changes shall be within the spirit and scope of the present invention as defined by the appended claim.

Having thus set forth and described the embodiments of my invention, which is claimed is:

In a combined ash tray, signal and advertising device, an ash tray portion having an upwardly stamped circular portion, the latter having a plurality of openings angularly spaced apart from each other, an intermediate portion having a circular top wall extending integrally into an outwardly flared peripheral side wall, the bottom edges of the said side wall fitting snugly over

5

the said upwardly stamped circular portion of the said ash tray portion, the top wall of the said intermediate portion having a plurality of openings identical in number and vertically aligned with those of the said ash tray portion, the said intermediate portion being adapted to receive a battery, means for securing a socket for an electric bulb to the top wall of the said intermediate portion, the said socket being disposed above the said intermediate portion, a housing open at its bottom and having a top wall and side walls equipped with window openings, threaded studs extending from the said side walls of the housing downwardly equally numbered to that of the said openings in the said ash tray portion and the said intermediate portion respectively, the said studs being adapted to pass downwardly through the said openings of the said intermediate portion and the said ash tray portion and means for retaining the said studs in their position extending through the said openings, so that in the assembled position the said socket with the said electric lamp is disposed within the said housing.
